UNITED STATES PATENT OFFICE.

WILLIAM BERG, OF NEW YORK, N. Y., ASSIGNOR TO GENERAL OPTICAL COMPANY,
INC., A CORPORATION OF NEW YORK.

PERIMETER.

1,113,091.

Specification of Letters Patent.

Patented Oct. 6, 1914.

Application filed April 30, 1913. Serial No. 764,732.

To all whom it may concern:

Be it known that I, WILLIAM BERG, a citizen of the United States, residing at the city of New York, in the borough of Queens and State of New York, have invented certain new and useful Improvements in Perimeters, of which the following is a full, clear, and exact description.

This invention relates to perimeters and more especially to the self-registering type.

The object of my invention is to construct an instrument of this class which will be of simple and compact form.

In the apparatuses which heretofore have been constructed, the recording means consists of an intricate construction in which the elements are liable to get out of adjustment or to cause an error in the reading, due to lost or inaccurate motion between the parts.

It is therefore my purpose to construct an instrument which will obviate these objections and my invention consists in an instrument having recording means whose recording marker will be moved correspondingly to the travel of the test object by a direct and positive connection between the parts and in which the recording marker will move in a plane parallel to the plane of travel of the arc, the chart-plate being movable and adapted to be brought into position where the marker will register the correct angular position of the test object on the chart.

In the accompanying drawings, in which my improved perimeter is illustrated, Figure 1 is a side elevation thereof; Fig. 2 is a front elevation; Fig. 3 is a detail of the recording mechanism; Fig. 4 is a plan of a detail of the recording mechanism; and Fig. 5 is a detail of the profile plate.

The base of the instrument, indicated by 1, may be of any desired conformation and is provided with three supporting legs. A post 2, curved at its lower portion, is fastened at its lower end by any desired means to the front leg of the base; the upper end of this post acting to position the eye of the patient, as is common with instruments of this type. This post is slotted for the reception of a threaded stud-pin 3 carried by the chin-rest bracket 4. This bracket carries a stop-pin 5, which is held in firm engagement with a serrated portion of the

post by an expansion spring 6 resting 55 against a nut on the end of the pin 3, which insures that the bracket will remain in its adjusted position. A chin-rest 7 of the usual construction is rotatably mounted on said bracket by a similar pin and spring device, so that it may be swung from one side to another in order to bring each eye of the patient in turn opposite the upper end of the post. The rear portion of the base 1 is curved rearwardly as at 8, and then upwardly as at 9, terminating in a horizontal bearing 10. An arcuate frame 11 comprising a strip of brass or the like which is relatively broad and thin, but of sufficient strength to form a substantially rigid structure, is attached to a hollow revoluble sleeve 12 fitting in the bearing 10. This sleeve is enlarged at one end thereof to form a supporting surface, to which the arc is firmly secured by screws 14 inset in the surface of 75 the arcuate frame. The frame 11 is provided with a T-shaped groove 15 extending the entire length of the same in which a rack 16 is adapted to slide. Fastened at the upper end of this rack is a guide-strap 17 80 extending across the front surface of the frame and around the edges of the same into engagement with the rear surface. A color-shield 18, which carries the test object 19, is firmly secured to the strap so that the test 85 object will be positively moved by the rack. The arcuate frame 11 comprises a segment whose peripheral surface extends through an arc somewhat greater than 180 degrees, and the rack comprises a segment extending 90 substantially through 90 degrees, so that the test object may have a travel from the center of the field or arc to a point at substantially 90 degrees therefrom.

One of the bent-over portions of the strap 95 17 is provided with a pointer 17' which is adapted to ride over a graduated scale 11' on the rear of the arc, whereby the distance of the test object from the center of the arc or field may be easily read by the observer. 100 A removable dial 20 having a radial slot 21, fits over the hollow sleeve 12 between its support 13 and the enlarged portion of the bearing 10. This dial is held firmly against the enlarged end of the bearing 10 by a split 105 spring-washer 22 which holds the same against rotation with the revoluble sleeve 12. A pointer 23, attached to the rear surface of

the arcuate frame, rides over the outer edge of the dial 20 so that the meridian of the arc may be read on graduations 24 along the outer edge of this dial. This dial being of 5 relatively large diameter, also serves the additional purpose of concealing the hand of the observer from the eye of the patient. A hollow rotatable shaft 25 fits into the revoluble sleeve 12 and carries a pinion 26 at its 10 front end, which is firmly secured to the shaft. A circular recess is formed in the center of the arcuate frame in which this pinion seats, the recess cutting one edge of the T-shaped groove, so that the teeth of the rack 16 may be engaged by the teeth of the pinion. A circular plate 27 is provided with a hub 28 which is fitted over the end of the hollow shaft 25 and firmly secured thereto by a set-screw. When it is desired to 15 move the test object in the field, the observer rotates this plate, and motion will be transmitted to the test object through the mechanism described.

The recording means receives its motion 20 through a spiral groove or profile 29 cut in the rear face of the plate 27, which, as is clearly shown in Figs. 3 and 5, comprises a spiral having substantially nine complete turns, corresponding to the 90 degrees 25 through which the test object is adapted to be moved, the purpose of which will be hereinafter set forth. Mounted on the revoluble sleeve 12 is a guide bracket 31 which is firmly secured thereto, so that upon rotation of the arc and hollow sleeve, this guide bracket will also be rotated. This bracket is provided with right-angled portions which extend above and below the circular cam-plate 27, and has attached to the ends of the 30 same a guide-bar 32 upon which the guide-block or traveler 33 is movably mounted. The bar 32 is preferably rectangular in cross-section and is provided with a circular opening at the center thereof alining with 35 the opening in the hollow shaft 25. The block or traveler 33 consists of a rectangular sleeve which slides on the guide-bar and has fastened to one side thereof a pin 34 which rides in the spiral groove 29 of the plate 27.

It will therefore be seen that upon one revolution of the circular plate 27 the guide-block 33 will be moved a distance equal to the 40 distance between the centers of two adjacent grooves. A marker such as a pencil or 45 prick-pin 35, fastened to a metallic strip slotted for the reception of a set-screw, is adjustably mounted on the rear face of the rectangular guide-block 33 for engagement with a chart which is preferably supported 50 in the following manner. Extending substantially at right angles to the vertical portion 9 of the frame is a support 36 for the chart-plate 37. This plate is firmly fastened to a skeleton frame 38 by means of the 55 pins 39, the two free ends of the frame being 60

pivoted to up-standing lugs carried by the support 36. At the two front corners of this plate, shields 40 are mounted under which the corners of the chart (shown in dotted lines) are adapted to be slipped and at the 70 rear edge of the plate this chart is firmly retained in position by a spring-clamp 41 having a broad bearing surface 42. The plate is provided with cuts or gage-marks 43, which define the vertical and horizontal axes of 75 the plate and with which the horizontal and vertical axes of the chart should be alined for a purpose which will hereinafter be described in connection with the operation of the instrument.

In using the perimeter, a chart is firmly positioned upon the chart-plate with its horizontal and vertical axes alining with the gage-mark 43 on the same. The test object is moved until it is directly at the center 85 or zero point of the arc, *i. e.*, when pointer 17' is at zero point of the graduated scale 11' on the rear surface of the arc. The marker 35 having a corresponding movement, should now be positioned so that when 90 the chart is brought into engagement with the same, a point will be recorded at the exact center of the chart. If the point is off-center, the marker may be adjusted until exact registry is obtained, by means of the 95 set-screw which holds the marker in place. After the marker or prick-pin has once been adjusted, it is only necessary to aline the vertical and horizontal axes of the chart with the gage-marks 43 on the plate to insure that the centers of the arc and chart 100 will coincide when the chart-plate is rotated to bring the axes of the arc and chart into parallelism. When the marker or pin 35 is at the center or zero point of the arc, 105 it is to be noted that the pin 34 will not be seated in the end of the groove for this groove is continued for a portion of a turn beyond this point. If the operator should then carelessly move the test object toward 110 its zero position, the same will not be stopped until it has passed by the zero point a distance sufficient to warn the operator of this fact, which will diminish the chances of the pin 34 being forced against the end 115 of the groove hard enough to break or bend the same. The chin-rest is then adjusted to bring the eye of the patient upon an exact horizontal axis determined by the circular openings in the hollow shaft and guide-bar, 120 which openings determine the point at which the eye of the patient is to be directed and is usually known as the "fixation point". Assuming now that the arc is in a horizontal plane so that the pointer 23 will register 125 with zero graduation on the large dial 20, the test object will then be moved by revolving the cam-plate 27. The rack and pinion are so designed that upon one revolution of the cam-plate 27, the test object will move 130

10 degrees along the arcuate frame 8. The prick-pin or marker 35 due to its positive and direct connection with the spiral groove in the plate 22, will be moved the distance between two adjacent grooves which corresponds to the distances between two of the circles on the chart representing 10 degrees. The parts of the recording mechanism are therefore so proportioned that the movement of the test object along its arcuate frame will be reproduced by the marker 35 moving along its guide-bar 32, so that upon bringing the chart into engagement with this marker, the exact angular distance which the test object has been moved will be recorded. After a predetermined point has been recorded in the horizontal plane, which need not further be described but will determine the extent of the patient's range of vision along this axis, the arcuate frame 11 is then moved to various other angular positions. In each position a point is recorded which will determine the extent of the range of vision along that meridian until points have been determined for the entire angular movement of the arc from which the field of vision of the patient may be plotted. After one eye of the patient has been tested, the chin-rest is swung to the other side and the other eye is tested in a similar manner. I desire to particularly emphasize that since the guide-bracket is positively connected to the hollow sleeve carrying the arcuate frame 11, there is no possibility of any lost motion between these two parts, and as the pin 34 fits closely within the spiral groove, an error due to lost motion from this source is precluded. It will also be obvious that the recording means is of marked simplicity, having no parts which necessitate fine adjustment to obtain precise measurements, making it possible to produce an accurate instrument of this type at a materially decreased cost.

45 Having thus described my invention, I claim:—

1. In an instrument of the class described, a revoluble arc, a test object movably mounted thereon, means for moving said test object including a rotatable member, revoluble with said arc, recording means having a marker, and means operatively associated with said member for moving said marker correspondingly to the movement of the test object.

2. In an instrument of the class described, an arc revolubly mounted on a hollow sleeve, a rack slidably mounted on said arc and carrying a test object, a shaft passing through said hollow sleeve having a pinion in engagement with said rack, means for rotating said shaft, and means operatively associated with said means for recording the position of the test object.

65 3. In an instrument of the class described,

the combination with a revoluble arc having a movable test object mounted thereon, means for moving said test object, means for recording the position of said test object including a rotatable member connected to said first named means having a spiral groove in the face thereof, and a marker adapted to travel in said groove.

4. In an instrument of the class described, a revoluble arc, a rack slidably mounted thereon carrying a test object, a pinion and a rotatable member connected thereto for moving said rack, said pinion and rotatable member being revoluble with said arc, and recording means also revoluble with said arc having a movable marker operatively associated with said rotatable member for moving said marker correspondingly with the movement of said test object.

5. In an instrument of the class described, a revolubly mounted arc, a test object movably mounted on said arc, shifting means therefor, a recording mechanism including a marker connected to said shifting means and arranged to be revolved with said arc and to be moved correspondingly to the movement of the test object both of said movements being in a plane substantially parallel to the plane of rotation of said arc.

6. In an instrument of the class described, an arc revolubly mounted on a hollow sleeve, a rack movably mounted on said arc carrying a test object, a shaft passing through said hollow sleeve having a pinion for engagement with said rack, means on said shaft provided with a spiral groove, recording means, means for supporting the same, said supporting means being revoluble with said arc, and means co-acting with said spiral groove for moving said recording means correspondingly with the movement of the test object.

7. In an instrument of the class described, a revolubly mounted arc, a rack carrying a test object slidably mounted thereon, a pinion engaging with said rack for moving the test object, a rotatable member connected to said pinion and revoluble with said arc, and means co-acting with said rotatable member for recording the position of the test object in the field of vision.

8. In an instrument of the class described, an arc revolubly mounted on a hollow sleeve, a rack slidably mounted on said arc carrying a test object, a shaft passing through said hollow sleeve having a pinion thereon for engagement with said rack, and a marking device revoluble on an axis parallel to the axis of rotation of said arc and connected to said shaft for moving said marking device correspondingly with the movement of said test object.

9. In an instrument of the class described, the combination with a movable test object

and means for moving the same to any point within the field of vision, and means for recording the position of the test object comprising a rotatable plate connected to said first-named means, said plate having a spiral groove therein and a marking device adapted to travel in said groove.

In witness whereof, I subscribe my signature in the presence of two witnesses.

WILLIAM BERG.
